UNITED STATES PATENT OFFICE.

ENDO L. BELL, OF BERKLEY, VIRGINIA.

SIGN-SUPPORT.

No. 805,622.

Specification of Letters Patent.

Patented Nov. 28, 1905.

Application filed May 26, 1905. Serial No. 262,466.

To all whom it may concern:

Be it known that I, ENDO L. BELL, a citizen of the United States, residing at Berkley, in the county of Norfolk and State of Virginia, 5 have invented a new and useful Sign-Support, of which the following is a specification.

This invention relates to devices for supporting signs, more particularly for use in connection with railway-tracks for designating the various switch-tracks and the like; and it has for its object to produce a simply-constructed device whereby a sign-plate may be easily and quickly arranged in position and changed when required.

15 With these and other objects in view, which will appear as the nature of the invention is better understood, the same consists in certain novel features of construction, as hereinafter fully described and claimed.

20 In the accompanying drawings, forming a part of this specification, and in which corresponding parts are denoted by like designating characters, is illustrated the preferred form of embodiment of the invention capable 25 of carrying the same into practical operation.

In the drawings thus employed, Figure 1 is a perspective view of the improved device applied. Fig. 2 is a perspective view of the supporting-frame detached and without the sign-plate.

30 The improved device comprises a vertical open frame having guides at the ends for receiving the ends of a sign-plate and a rest at the lower side for bearing beneath the sign-plate and with a lateral projection forming 35 a base for connection to a support, such as a railway-tie.

The device is preferably formed from a single sheet of metal, with a central aperture 40 formed transversely through the same and a little smaller than the sign-plate, to be supported and folded over upon itself at the ends, as at 10 11, to form vertical guides for the ends of the sign-plate, (represented at 12,) and with 45 the upper side folded over, as at 13, to strengthen the structure, and with a laterally-extending base, as at 14. The metal at the lower side of the aperture is provided with spaced slits 15, and the metal released thereby bent

in opposite directions, as in Fig. 2, to form a 50 rest for the lower edge of the sign-plate to limit its downward movement. If it is required to secure the sign-plates in position, transverse apertures, as at 16, will be provided to receive binding wires, rivets, or similar 55 fastenings.

The lateral base-extension portion 14 is provided with apertures 17 to receive the holding members, such as railway-spikes, as at 18, by which the device may be fastened to the 60 tie 19 adjacent to the rail 20 and in position to be readily seen by the members of the train crew, switchmen, or others whose business it is to know what the sign denotes.

In railway-yards and like localities much 65 annoyance, delay, and frequently serious accidents occur from lack of knowledge regarding switches, side tracks, and the like, and the improved device herein illustrated is admirably adapted for denoting the numbers 70 and other facts concerning switches, switch-tracks, and the like. The device being of relatively small size will not interfere with the ordinary uses of the tracks, while at the same time is in the best place to impart the 75 desired information. The sign-plates can be readily changed when required or renewed at small cost when worn or broken or the lettering or numbers become obliterated from exposure.

Having thus described the invention, what is claimed is—

The herein-described sign-support formed from a single sheet of metal with a transverse aperture and a lateral projection forming a 85 supporting-base, the metal folded upon itself at the ends to form guides for the sign and folded upon itself at the top to strengthen the structure and with spaced slits at the lower side of the aperture for bending in opposite 90 directions to form a bearing for the sign.

In testimony that I claim the foregoing as my own I have hereto affixed my signature in the presence of two witnesses.

ENDO L. BELL.
